CLAIM

The ornamental design for a wireless charger, as shown and described.

DESCRIPTION

FIG. 1 is a top, front, right side perspective view of a wireless charger showing my new design;

FIG. 2 is a bottom, back, right side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a top, front, right side perspective view of the wireless charger of FIG. 1, shown in a condition for use; and,

FIG. 10 is a bottom, back, left side perspective view thereof.

The broken lines shown in the drawings depict portions of the wireless charger that form no part of the claimed design.
